UNITED STATES PATENT OFFICE.

BELONIE JANELLE, OF MANCHESTER, NEW HAMPSHIRE, ASSIGNOR OF THREE-FOURTHS TO HERMAN F. STRAW AND HARRY E. PARKER, OF SAME PLACE.

FILLING-SUPPLYING MECHANISM FOR LOOMS.

SPECIFICATION forming part of Letters Patent No. 651,716, dated June 12, 1900.

Application filed September 30, 1899. Serial No. 732,142. (No model.)

To all whom it may concern:

Be it known that I, BELONIE JANELLE, of Manchester, county of Hillsborough, State of New Hampshire, have invented an Improvement in Filling-Supplying Mechanism for Looms, of which the following description, in connection with the accompanying drawings, is a specification, like letters on the drawings representing like parts.

10 In the "Northrop" type of looms provided with automatic filling-supplying mechanism a plurality of filling-carriers are held separately in a movable feeder, which latter is actuated by a strong spring to bring the filling-carriers one by one into operative position to be transferred, such a loom being shown in United States Patent No. 529,940, dated November 27, 1894. The feeder there-
15 in shown is circularly movable, and it is in-
20 termittingly moved by the spring to bring the filling-carriers into the path of a trans-
ferrer, the spring being wound automatically after each transfer, the filling-carrier next to be removed being held by the force of the
25 spring against a fixed stop, so that the trans-
ferrer forces the filling-carrier from the feeder against such stress of the spring. This subjects the filling-carriers to consider-
able strain and materially decreases their
30 life, and the use of the spring necessitates considerable mechanism to operate it. In my efforts to simplify the construction of the filling-supplying mechanism and to over-
come the stress of the spring against which
35 the filling-carriers are transferred I have devised a gravity-actuated feeder normally held at rest with the filling-carrier next to be engaged by the transerrer in operative po-
sition, the feeder at the time of transfer be-
40 ing unlocked and free to accommodate itself to the movement of the transerrer.

Various novel features of my invention will be hereinafter described and particularly pointed out in the claims.

45 Referring to the drawings, Figure 1 is a transverse sectional view of a portion of a loom, taken inside the filling-supplying mechanism and illustrating one embodiment of my invention. Fig. 2 is a plan view of

the filling-supplying mechanism; and Fig. 50
3 is a transverse section on the line xx , Fig.
2, looking toward the left.

The loom-frame A, lay A³, slotted below one of the shuttle-boxes, as at 10, Fig. 3, the breast-beam A⁴⁰ and bunter C², the self-threading shuttle S, the filling-supplying mechanism consisting essentially of a notched disk a to receive the heads of the filling-carriers b, and a second disk a' to hold their tips or small ends, the disks being connected 60 and mounted to rotate on a fixed stud a⁶, se-
cured to a stand a', and the transerrer f',
mounted on a stud f, may be and are sub-
stantially as in the patent referred to, the
controlling mechanism being substantially 65 the same as in United States Patent No.
568,455, dated September 29, 1896, the dog
m^x being governed as to its position by or
through the rock-shaft d' and intervening
connections. The connected disks a a' of the 70
feeder are mounted to rotate freely on the
stud a⁶, and a pointed-tooth star wheel or
ratchet a¹⁰ is herein shown as located at the
inner side of and to rotate with the disk a,
the spaces between the teeth of the ratchet 75
corresponding in number and radial arrange-
ment to the holding devices for the filling-
carriers, the latter being arranged circularly
relative to the axis of the feeder, as in the
patents referred to. The transerrer f', hav-
ing the finger 21 to engage the tip of a fill-
ing-carrier, projects between the disks, and,
viewing Fig. 3, it will be manifest that owing
to this location the greatest number of filling-
carriers which can be placed in the feeder 85
will not completely fill it, and the resultant
or preponderant weight of the load carried
by the feeder will be located eccentrically to
and at that side of the center of gravity op-
posite the transerrer. Consequently this ec-
centricity of the load will, when the feeder 90
is free to move, cause its rotation through
the action of gravity in the direction of the
arrow 30, Fig. 3, to bring one filling-carrier
after another into operative position in the 95
path of the transerrer, the filling-carrier b^x
being the one next to be transferred.

I have herein shown a detent or dog f¹⁰ to

coöperate with the ratchet a^{10} and normally lock the feeder from movement, said detent being controlled by or through the transferrer, and as the simplest construction the 5 detent is secured to or forms a part of the transferrer f' , projecting upwardly therefrom to engage the ratchet when the transferrer is retracted. Referring to Fig. 3, it will be seen that not only is the feeder thus locked, but 10 it is accurately positioned to insure the location of the filling-carrier next to be transferred in the transferrer-path. Supposing that with the parts in the position shown in Fig. 3 a transfer is to be effected, then the downward 15 movement of the transferrer causes the disengagement of the detent and ratchet, so that the feeder is free during transfer, permitting the filling-carrier to adjust itself, if necessary, to the transferrer. After transfer and 20 as the transferrer returns to normal position the feeder will be advanced, as has been described, until the next space on the ratchet a^{10} is in position to be entered by the detent, the latter then locking the feeder and completing 25 the accurate positioning of the next filling-carrier in the series by engagement of the detent with the side of the adjacent tooth.

The stoppage of the feeder and the locking in position thereof are entirely independent 30 of the filling-carriers, and the latter are not subjected to any strain or shock other than that due to engagement by the transferrer.

With the mechanism herein shown damaged filling-carriers can be used as well as 35 perfect ones, so long as they can be held in the feeder, owing to the fact that the filling-carrier plays no part in positioning itself or the feeder.

To prevent any accidental retrograde movement of the feeder, I have herein shown it as 40 provided with an external toothed wheel a^9 , with which coöperates a pawl e^{25} , Figs. 1 and 2.

It will be manifest that my invention is 45 readily embodied in the well-known Northrop type of filling-supplying mechanism by the removal of the feeder-actuating spring and the spring-winding device and adding the locking-detent and coöperating ratchet, as herein described.

50 My invention is not restricted to the exact details and arrangement herein shown, for I have illustrated one practical embodiment thereof without attempting to show the various modifications which might be made 55 therein.

Referring to Fig. 3, it is clear that the resultant weight of the load of the feeder will be eccentric to the center of gravity of the latter until the last filling-carrier has been 60 moved into position to be transferred.

So far as I am aware I am the first to devise filling-supplying mechanism for looms wherein gravity is relied upon to impart movement to the feeder to bring the filling- 65 carriers into operative position, thus enabling me to dispense with mechanism to effect such

movement, and it is intended to herein broadly cover the action of gravity for such purpose.

In the apparatus herein shown the transferrer acts to control the gravity-actuated 70 movement of the feeder to place the filling-carriers singly in the path of the transferrer; but such control of the feeder-moving means forms the subject-matter of claims in another application, Serial No. 732,141, filed concurrently by me.

Having fully described my invention, what I claim as new, and desire to secure by Letters Patent, is—

1. A movable filling-feeder having its load 80 of filling-carriers disposed eccentrically relative to its center of gravity, whereby gravity when free to act will effect movement of the feeder, and means independent of the filling-carriers to normally hold the feeder against 85 gravity actuation.

2. A gravity-actuated filling-feeder to hold a series of filling-carriers, a transferrer to engage and remove the latter one by one, and a 90 detent for the feeder, independent of the filling-carriers and controlled by or through the transferrer.

3. A rotatable filling-feeder adapted to hold a circularly-arranged series of filling-carriers with their resultant weight located eccentric 95 to its axis, a transferrer to engage and remove one filling-carrier after another as they are brought into position by gravity-induced movement of the feeder, and means to at times hold the feeder against movement independently of the filling-carriers. 100

4. A filling-feeder movable intermittently by gravity to bring the filling-carriers supported thereby into operative position one by one, and means independent of the filling- 105 carriers to terminate such movement of the feeder and to at the same time complete the positioning of the filling-carrier next to be removed.

5. A filling-feeder movable intermittently 110 by gravity to bring the filling-carriers supported thereby into operative position one by one, a transferrer to engage and remove the positioned filling-carrier, and a detent for the feeder, the latter being released at the time 115 of engagement of the transferrer with a filling-carrier.

6. A movable filling-feeder having its load 120 of filling-carriers disposed eccentrically to its center of gravity, whereby gravity when free to act will effect movement of the feeder, a transferrer to engage and remove the filling-carriers one by one, a detent movable with the transferrer, and a ratchet movable with the feeder, engaged by the detent on return 125 of the transferrer to normal position, to lock the feeder and position the filling-carrier next to be removed.

7. A rotatable filling-feeder to hold a series 130 of filling-carriers, a ratchet rotatable with the feeder, the latter when free to move being actuated by gravity to bring the filling-car-

riers singly into operative position, a trans-
ferrer to engage the filling-carrier next to be
removed, and a detent on said trans-
ferrer, movable into engagement with the ratchet
5 when the trans-
ferrer is retracted, to maintain
the feeder at rest and to accurately position
the filling-carrier next to be engaged by the
trans-
ferrer.

8. In a loom, the lay, its shuttle-box, a
10 trans-
ferrer, a circularly-movable feeder to
hold a series of filling-carriers, an attached
ratchet, a coöperating dog movable by or
through retraction of the trans-
ferrer to engage the ratchet and lock the feeder from
15 movement, the resultant weight of the filling-
carriers located eccentric to the axis of the
feeder operating to rotate the latter when re-
leased, to bring the filling-carriers singly into
position to be acted upon by the trans-
ferrer,

the feeder at the time of transfer being un- 20
locked.

9. A rotatable filling-feeder adapted to hold
a circularly-arranged series of filling-carriers
with their resultant weight at one side of its
axis, a trans-
ferrer movable at the opposite 25
side of said axis to engage and remove one by
one the filling-carriers as the feeder is moved
by gravity to bring them into operative posi- 30
tion.

In testimony whereof I have signed my
name to this specification in the presence of
two subscribing witnesses.

BELONIE JANELLE.
